UNITED STATES PATENT OFFICE.

JAMES F. STEFFA, OF ROCKVALE, ILLINOIS.

VELOCIPED.

SPECIFICATION forming part of Letters Patent No. 375,961, dated January 3, 1888.

Application filed April 16, 1887. Serial No. 235,068. (No model.)

To all whom it may concern:

Be it known that I, JAMES FRANKLIN STEFFA, of Rockvale township, in the county of Ogle and State of Illinois, have invented a new and Improved Motor, of which the following is a full, clear, and exact description.

The object of my invention is to provide a new and improved motor adapted for traction or stationary purposes, for running light machinery, for transporting light material, and for various other purposes.

The invention consists in the construction and arrangement of the various parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a sectional side elevation of my improvement on the line $x\ x$ of Fig. 2. Fig. 2 is a sectional plan view of the same on the line $y\ y$ of Fig. 1. Fig. 3 is a vertical cross section of the same on the line $z\ z$ of Fig. 1, looking in the direction of the arrow z' . Fig. 4 is a front elevation of the forward part of my machine. Fig. 5 is a sectional plan view of part of my improvement on the line $u\ u$ of Fig. 3. Fig. 6 is an enlarged sectional side elevation of part of the same on the line $v\ v$ of Fig. 5, looking in the direction of the arrow v' . Fig. 7 is an enlarged sectional side elevation of the same on the line $v\ v$ of Fig. 5, looking in the direction of the arrow v^2 . Fig. 8 is an enlarged sectional side elevation of part of my improvement on the line $w\ w$ of Fig. 5. Fig. 9 is a similar sectional plan view of the same on the line $w'\ w'$ of Fig. 8. Fig. 10 is an end elevation of the operator's seat, parts being in section on the line $t\ t$ of Fig. 1. Fig. 11 is an enlarged side elevation of the stirrup of the steering device. Fig. 12 is a plan view of the lock and indicator of the steering device, and Fig. 13 is an enlarged side elevation of the brake shoe and its connection.

The main frame A, of suitable size and shape, is secured at its rear end to the axle B, carrying the main driving-wheels B', loosely mounted on the said axle B. The front part of the frame A is supported on the steering-frame C, adapted to tilt sidewise on the king-

bolt C', held on the said front part of the frame A, and in the steering-frame C are mounted the steering front wheels, C². On the inside 55 of each of the main driving-wheels B' is secured a gear-wheel, B², engaging a pinion, D', secured to a shaft, D, mounted in a frame, E, adapted to slide up and down in suitable guides, E', formed on the main frame A, so 60 that the pinions D' can be thrown in and out of contact with the said gear-wheels B². The frame E can be raised or lowered by the adjustable lever E², connected by its inner end with the middle of the said frame E, and being pivoted at E³ to a bracket, E⁴, secured to the main frame A. The bracket E⁴ is provided with a segmental arm, E⁵, having notches to engage corresponding lugs formed on one side 65 of the lever E² near its outer handle end, as 70 shown plainly in Figs. 1 and 2. The lever E² is thus held in a locked position by the lugs engaging the notched on the segmental arm E⁵.

Each shaft D is adapted to slide up and down with its frame E, and also adapted to slide endwise in its bearings on the said frame by the shifting-lever D², (see Figs. 5 and 7,) pivoted by its lower end to the frame E, and adapted to engage at its upper handle end the notches E⁶, formed on the plate E of the frame E. The 75 shifting-lever D² operates against a collar, D³, held loosely on the shaft D, and to the said collar D³ is secured one end of the spring D⁴, coiled on the shaft D, and secured at its other end on the collar D³, adapted to slide on and 80 turn with the shaft D by means of the screw D⁵, screwing on the collar D³ and engaging a slot, D⁶, formed on the said shaft D. (See Figs. 5, 6, and 7.) On the inner end of each shaft D is secured a clutch-wheel, D⁸, adapted to engage a 85 similar clutch-wheel, F', fastened at the outer end of the main driving-shaft F, held transversely in suitable bearings on the frame E in line with the said shafts D.

On the shaft F is secured a gear-wheel, F², 95 on, which operates a driving mechanism. (Illustrated in detail in Figs. 8 and 9.) This mechanism is provided with a forward and backward rocking frame, G, having an arm, G¹, pivoted on the upper end of the weighted lever H, 100 fulcrumed on an arm, H¹, secured to the sliding frame E. The frame G is provided with two parallel hollow arms, G² and G³, respectively open at the inside and inclosing two op-

posite edges of the gear-wheel F^2 , which is guided in the said hollow arms. In each of the said arms G^2 and G^3 is hung on a bolt, G^4 , a bar, G^5 , adapted to slide on the bolt G^4 , but being held in an innermost position on the inner end of the bolt G^4 by a spring, G^{60} , resting against the respective arms G^2 or G^3 , and pressing on the ends of the said bars G^5 . On each of the latter are pivoted a number of inwardly-projecting pawls, G^6 , pivoted to a second bar, G^7 , pivotally connected to one end of the lever G^8 , fulcrumed in its middle on a link, G^9 , pivoted on the main frame G in line with the pivot of the latter and the center of the shaft F .

15 The pawls G^6 of the upper and lower bars, G^5 , stand in opposite directions to each other and engage the teeth of the gear-wheel F^2 on the forward and backward rocking motion of the frame G , thus turning the wheel F^2 and its shaft F in one direction. The position of the pawls G^6 , however, can be changed, so as to turn the wheel F^2 either forward or backward, by shifting the lever G^8 , which is accomplished by an arm, H^2 , pivotally connected 20 with one end of said lever G^8 and provided with notches H^3 , adapted to engage a lug, G^9 , formed on the arm G^3 . The handle H^5 is formed on the outer end of the arm H^2 , and serves to raise the latter out of contact with the lug G^9 , and also serves to change the position of the lever G^8 by pulling or pushing on the handle H^5 of the arm H^2 . When the lever G^8 thus changes its position, then the pawls G^6 are caused to turn in opposite direction by the bars G^5 , so that the pawls G^6 will impart a reverse motion to the wheel F^2 on the backward and forward rocking motion of the frame G .

30

35

The arm G' of the rocking frame G is pivotally connected with the pitman I , extending upward toward the front of the machine, and pivotally connected at its upper end to the short arm of the rocking lever J , mounted to rock loosely on the rod K , secured transversely to the frame A . The upper long end of the 40 rocking lever J is connected by the pitman I' with the short end of the lever J' , mounted to rock loosely on the rod K' , secured transversely to the frame A . The long end of the rocking lever J' is connected by the pitman I^2 with the 45 short end of the rocking lever J^2 , mounted to rock loosely on the rod K , and the long end of this lever J^2 is connected by the pitman I^3 with the short end of the lever J^3 , mounted to rock on the rod K' . The long end of this lever J^3 is connected by the pitman I^4 with the short 50 end of the lever J^4 , mounted to rock loosely on the rod K , and the long end of this lever J^4 is connected by the pitman I^5 with the main U -shaped hand-lever J^5 , mounted to swing on the rod K' , being provided with a handle, J^6 , near its upper end. It will be seen that when the lever J^5 is moved forward and backward it imparts a rocking motion to the several levers J , J' , J^2 , J^3 , and J^4 , and a similar motion 55 to the frame G , rocking on the weighted lever H , thus imparting motion to the gear-wheel F^2 , as before described. The frame G can also

be rigidly attached to the pitman I by detaching the arm G' from the weighted lever-arm H' and bolting it to the pitman I by passing 70 a bolt through one of the outer holes in G' and through a hole in the pitman to fit it.

On one of the clutch-wheels F' on the shaft F is formed a sprocket-wheel, F^3 , connected by a sprocket-chain, F^4 , to the sprocket-wheel F^5 , secured to the shaft L , mounted transversely in suitable bearings on the main frame A , and carrying on each end a fly-wheel, L' . The sprocket-wheel F^3 is provided with several steps for increasing or diminishing the speed 80 of the shaft L when the chain F^4 is changed and passed over the respective step of the sprocket-wheel F^5 . Instead of the sprocket-chain F^4 , I may use a belt. In order to take up the slack of the chain F^4 , caused either by 85 the up-and-down movement of the frame E , carrying the said sprocket chain-wheel F^3 , or by changing the chain F^4 to a smaller step on the sprocket-wheel F^5 , I provide the sprocket chain-tightening wheels N and N' , of which the wheel N is mounted on a lever, N^2 , pivoted on its upper end on the main frame A , and engaging, by means of a slot in its lower end, a segmental arm, N^3 , to which the lever N^2 can be fastened by a set-screw, N^4 . The other 90 tightening-wheel, N' , is mounted on the end of a large bar, N^5 , guided in the keeper N^6 , secured to a cross beam of the main frame A , and held in any desired position by the U -shaped clamp N^7 , held engaged with the notches of the bar N^5 by a spring, N^8 , pressing the said clamp N^7 downward. (See Fig. 1.) The tightening-pulleys N and N' are moved inward or outward, according to circumstances, to tighten the chain F^4 by moving 95 their respective lever N^2 or the bar N^5 and fastening the same in position by the set-screw N^4 and the U -shaped clamp N^7 , respectively. The chain belt-tightener wheels N and N' need not be sprocket wheels, but may be smooth-faced pulleys.

The steering-frame C , yielding sidewise on the king-bolt C' and supporting the wheels C^2 , consists of the cross-beam C^3 , turning on the said king-bolt C' , and forming on each outer end a bearing for the pin C^4 , secured to the U -shaped frame C^5 , in each of which a steering-wheel, C^6 , is mounted. The pins C^4 carry the sprocket-wheels C^6 , over which passes the sprocket-chain C^7 , also passing over the 120 sprocket-wheel C^8 , secured to the vertical shaft O , held on its lower part in a bearing formed of a cross beam of the main frame A , and on its upper part is journaled in a plate, O^2 , secured to the top of the main frame A on one 125 side.

On the lower end of the shaft O is pivoted a shoe, O^3 , adapted to turn the shaft O , and also used for operating the lock holding the shaft in position. This lock consists of an arm, P , pivoted to the upper end of the shaft O , and provided on its outer end with a lug adapted to engage notches O^4 , formed in a half-circle 130 on top of the plate O^2 . The arm P is held in

contact with the said notches by a spring, P', and can be raised out of contact with the said notches by a rod, P², pivotally connected with the said arm P and with the front end of the shoe O³. On the outer end of the arm P is also secured a handle, P³, for lifting the said arm out of contact with the notches O⁴ by hand.

The rear wheels, B', are braked by brake-shoes Q, pivotally connected with the crank-arms Q', secured to the shaft Q², held in suitable bearings on the main frame A. The shaft Q is provided with a downwardly-extending arm, Q³, connected by the link Q⁴ with a lever, Q⁵, pivoted on the main frame A, and provided on its upper end with a lug, Q⁶, adapted to engage corresponding notches formed on the segment Q⁷, secured to the main frame A on one side. Each brake shoe Q is held on its respective crank-arm Q' by a pin, Q⁸, passing through the said crank-arm and held in a slot, Q⁹, formed on the outside of the said brake-shoe Q in such a manner that the inner part of the brake-shoe rests on the inner end of the said pin Q⁸, as shown in Fig. 13.

On the rear end of the frame A is placed a platform, A', above which are held one, two, or more seats, R, each secured to springs R', fulcrumed on the upper end of a rod, R², extending downward through a slot, R³, formed in the standard R⁴, erected on the main frame A. Each rod R² is provided near its upper end with an extension, R⁵, having a lug, R⁶, on which the said spring R' rests, thus preventing the spring R' from turning downward and at the same time allowing the spring to yield when the seat is occupied.

On each extension R⁵ is secured a downwardly-extending notched spring-bar, R⁷, adapted to engage with its notches a beveled shoulder formed on the standard R⁴ in the said aperture R³, as plainly shown in Fig. 1. The notched bar R⁷ thus rests on the said beveled shoulder, and thereby supports the extension R⁵, the bar R², and the seat R. The notched bar R⁷ can be raised or lowered by pressing the said bar outward, thus disengaging the notches from the beveled shoulder and moving the entire seat up or down until the required height is obtained, after which one of the notches in the bar R⁷, when releasing the pressure on the said bar, again engages the beveled shoulder on the standard R⁴. The springs R' on each seat R, on account of being pivoted on the bar R², permit of throwing the seat R backward whenever desired, as shown on one side of Fig. 2, thus giving more room for the operator on the platform A'.

The operation is as follows: When it is desired to use the motor for traction purposes, then the frame E is moved into its lowest position by the arm E², so that the gear-wheels D' engage the gear-wheels B² on the main wheels B'. The shifting-levers D² are then moved into the position shown in Fig. 3 and to the left in Fig. 5, so that the clutch-wheels D⁸ engage the clutch-wheels F' on the shaft F. The operators on the seats R take hold of the

handle J⁶ of the U-shaped lever J⁵, and move the same forward and backward, so as to impart a rocking motion to the several levers, J, J', J², J³, and J⁴, and by means of the last pitman I impart a similar rocking motion to the frame G, which by its pawls G⁶ turns the gear-wheel F² and its shaft F. As the shaft F is connected with the main shaft D, and the same carries the gear-wheels D', meshing into the gear-wheels B², it will be seen that a rotary motion is imparted to the main driving-wheels, thus propelling the machine. The shaft F also imparts a rotary motion to the shaft L by means of the sprocket-wheels F³ and F⁴ and the sprocket chain F⁵, so that the fly-wheels L' insure a constant motion of the said shafts L and F. The operator can also steer the machine by placing one foot in the shoe O³ and by pressing the rear end of the shoe downward with his heel so as to lift, with the rod P², the arm P out of contact with the notches O⁴, thus permitting the turning of the shaft O by turning the said shoe O³ to one side, either to the right or left, according to the steering desired. The turning motion of the shaft imparts motion to the sprocket-chain C', whereby the sprocket-wheels C⁶ on the steering-frame C are turned, thus turning the steering-wheels C² simultaneously in one direction, either to the right or left, according to the movement given to the shaft O by the foot of the operator. The operator may also steer the apparatus by operating the arm P by hand by taking hold of the handle P³ and lifting the same and then turning the arm P, whereby the shaft O is also turned and causes the sprocket-chain C' to operate on the sprocket-wheels in the same manner, as above described. The notches O⁴ are numbered, as shown in Fig. 12, so as to indicate the degree to which the wheels C² are swung from their normal position. The operator can brake the wheels B' by moving the lever Q⁵ backward, so that the shoes Q are swung into contact with the rims of the wheels B'.

When it is desired to use the machine as a stationary power, then the operator disengages the lever E² from the notches in the segmental arm E⁵ and presses the said lever downward, so that the frame E is moved upward in its guides E', whereby the gear-wheels D' are disconnected from the gear-wheels B². The shifting-levers D² are then moved outward to engage the outer notches, E⁶, of the plate E⁷, as shown to the right in Fig. 5, whereby the clutch-wheels D⁸ are disengaged from the clutch-wheels F'. The rotary motion imparted to the shaft F, as before described, is transmitted to the shaft L, and can be utilized in any suitable manner by connecting said shaft L or its fly-wheels L' with the machinery to be driven.

The gear B² and wheel F³ may be changed in size, so as to increase or diminish the speed and power of the machine when used for traction purposes. The sliding frame E permits any change of said gear-wheels, as it can be raised or lowered to any desired height by the

lever E² and held in the said raised or lowered position. The power of the pitmen I, I', I², &c., the levers J, J', &c., can also be changed by adjusting the pivot-points nearer to or farther from the fulcrum K or K', and also by adjusting the last pitman, I⁵, up or down on the operating-lever J⁵.

Having thus described my invention, what I claim as new, and desire to secure by Letters Patent, is—

1. In a motor, the combination, with the drive-wheels, a main driving-shaft, and means for operating the drive-wheels from said shaft, of an auxiliary driving-shaft and means for disconnecting the main driving shaft from the driving-wheels and operating the auxiliary driving-shaft from the main shaft, substantially as and for the purpose set forth.

2. In a motor, the combination, with the supporting-frame and drive-wheels provided with gear-wheels, of a driving-shaft provided with gear-wheels meshing with the gear-wheels of the driving-wheels, and having a vertical and sidewise movement, and means for operating the said driving-shaft, substantially as herein shown and described.

3. In a motor, the combination, with a driving-shaft provided with a gear-wheel, of a reciprocating frame carrying reversible pawls engaging said gear-wheels, a hand lever, and intermediate mechanism between the hand-lever and the reciprocating frame, substantially as herein shown and described.

4. In a motor, the combination, with the main driving-shaft F and the gear-wheel F², mounted on the same, of the pawls G⁶, operating on the teeth of the said gear-wheel F², the yielding bars G⁵, supporting the said pawls G⁶, and the rocking frame G, adapted to move forward and backward so as to impart by its pawls G⁶ motion to the said gear-wheel F² and the main shaft F, substantially as shown and described.

5. In a motor, the combination, with the main driving-shaft F and the gear-wheel F², secured on the said shaft, of the pawls G⁶, engaging the two sides of said gear-wheel F², a yielding bar supporting the said pawls G⁶, the rocking frame G, supporting the said yielding bars G⁵, and the weighted lever H, on which the said frame is fulcrumed, substantially as shown and described.

6. In a motor, the main shaft F and the gear-wheel F², secured on the said shaft F, combined with the pawls G⁶, adapted to engage the said gear-wheel F² on two opposite sides, the bar G⁵, carrying said pawls G⁶, the bolt G⁴, supporting said bar G⁵, the spring G⁶⁰, adapted to press on said bar G⁵, and the swinging frame G, having two hollow arms, G² and G³, each supporting one bolt G⁴, substantially as shown and described.

7. In a motor, the rocking frame G, having two hollow arms, G² and G³, the bolts G⁴, supported in the said hollow arms, the yielding bars G⁵, held on said bolts G⁴, and the pawls G⁶, pivoted on said bars G⁵, in combination

with the bars G⁷, pivotally connected with the said pawls G⁶, the lever G⁸, pivotally connected at opposite ends from its fulcrum with the said bars G⁷, the link G⁹, connecting the bar G⁸ with said frame G, and means, substantially as described, for changing the position of said lever G⁸, as set forth.

8. In a motor, the rocking frame G, having two hollow arms, G² and G³, the bolts G⁴, supported in said hollow arms, the yielding bars G⁵, held on said bolts G⁴, and the pawls G⁶, pivoted on said bars G⁵, in combination with the bars G⁷, pivotally connected with said pawls G⁶, the lever G⁸, pivotally connected at opposite ends from its fulcrum with said bars G⁷, the link G⁹, connecting the bar G⁸ with said frame G, the notched arm H², pivotally connected with one end of said lever G⁸, and adapted to engage by its notches a lug on said frame G, and the spring H⁴, holding said arm H² in contact with said lug, substantially as shown and described.

9. In a motor, the combination, with the main driving-shaft F and the clutch-wheels F', secured on the said shaft, of the clutch-wheels D⁸, adapted to engage said clutch-wheels F', the shafts D, carrying the said clutch-wheels D⁸, the fixed collar D³ on said shaft D, the spring B⁴, coiled on said shaft D and pressing against the fixed collar D³, the shifting-lever D², operating against said fixed collar D, and means, substantially as described, for holding said shifting-lever in position, as set forth.

10. In a motor, the combination, with the frame E, of the shaft D, having its bearings in the said frame E, the collar D³, fixed on said shaft D, the collar D⁵, held loosely on said shaft, a screw secured in the said collar D⁵, and engaging a slot, D¹, formed in said shaft D, so as to prevent said collar from turning, a shifting-lever, D², pivoted on said frame E and adapted to press on said loose collar D⁵, and the notched plate E¹, secured on said frame E and adapted to hold said shifting-lever D² in position, substantially as shown and described.

11. In a motor, the combination, with the frame E, adapted to slide vertically in suitable bearings, of the lever E², acting on the said frame E, the fixed bracket E⁴, on which said lever E is fulcrumed, the segmental arm E⁵ on the said bracket E⁴, notches formed on said segmental arm E⁵, and lugs secured on the said lever E² and adapted to engage said notches on the segmental arm, so as to hold said lever E² in any desired position, substantially as shown and described.

12. In a motor, the combination, with the steering-shaft O, adapted to operate the steering mechanism, of an arm, P, pivoted to the upper end of said shaft O, the plate O², provided with notches O⁴, in which is held in a locked position the said arm P, the shoe O³, pivotally connected with the said steering-shaft O, and the arm P², pivotally connected with said shoe O³, and said arm P, substantially as shown and described.

13. In a motor, the steering-shaft O, the arm P, pivoted on the upper end of the said shaft O, the notched plate O², for holding said arm in position, the spring P', holding said arm P in contact with the notches O⁴ on said plate O², in combination with the shoe O³, pivotally connected to said shaft O, the arm P², connecting said shoe O³ with said arm P, and the handle P³, secured to said arm P, substantially as shown and described.
14. In a motor, the steering-shaft O, the sprocket-wheel C⁸, secured on said shaft O, and the sprocket-chain C⁷, passing over said sprocket-wheel C⁸, in combination with the cross-beam C⁹, adapted to turn on the king-bolt of the main frame, the pins C⁴, held in bearings on the outer ends of said cross-beam C⁹, the sprocket-wheels C⁶, secured on said pins C⁴ and operated by said sprocket-chain C⁷, the U-shaped frames C⁵, carrying said pins C⁴, and the steering-wheels C², mounted in said U-shaped frames C⁵, substantially as shown and described.
15. In a motor, the combination, with the driving-wheels B', of the brake shoes Q, held near the rims of said wheels B', the crank-arms Q', supporting said shoes Q, the pin Q⁸, secured on each of said crank-arms Q' and engaging a slot, Q⁹, formed in each of said brake-shoes Q, the shaft Q², supporting said crank-arms Q', the arm Q³, secured to said shaft Q², the link Q⁴, pivotally connected with said arm Q³, the lever Q⁵, connected with said link Q⁴, the lug Q⁶, formed on said lever Q⁵, and the notched segmental plate Q⁷, secured to the main frame and adapted to hold said lever Q⁵ in position, substantially as shown and described.
16. In a motor, the combination, with the main driving-shaft F and the sprocket-wheel F³, secured to the said shaft F, of the sprocket-chain F⁴, actuated by said sprocket-wheel F³, sprocket-wheel F⁵, operated by said sprocket-chain F⁴, the shaft L, carrying said sprocket-wheel F⁵, and the fly-wheels L', secured on said shaft L, substantially as shown and described.
17. In a motor, the frame E, adapted to slide vertically, the shaft F, mounted in said frame, and the sprocket-wheel F³, secured to said shaft F, in combination with the sprocket-chain F⁴, actuated by said sprocket-wheel F³, the sprocket-wheel F⁵, operated by said sprocket-chain F⁴, the fly-wheel shaft L, supporting said sprocket-wheel F⁵, the tightening-wheels N and N', over which passes said sprocket-chain F⁴, and means, substantially as described, for changing the relative position of said chain-wheels N and N', as set forth.
18. In a motor, the sprocket-wheels F³ and F⁵ and the sprocket-chain F⁴, passing over said sprocket-wheels F³ and F⁵, in combination with the chain-tightening wheel N', the notched arm N⁵, supporting said wheel N', the U-shaped clamp N⁷, adapted to engage the notches in said arm N⁵, the spring N⁸, for holding said clamp in contact with the notches of said arm N⁵, and a keeper, N⁹, supporting said arm N⁵, and the U-shaped clamp N⁷, substantially as shown and described.
19. In a motor, the combination, with the standards R⁴, having a slot, R³, of the rod R², passing through said slot, the notched bar R⁷, also passing through said slot, the extension R⁵, secured to said rods R² and R⁷, the springs R', pivoted on said extensions R⁵ and resting on the lug R⁶ of said extensions, and the seat R, supported by said springs R', substantially as shown and described.
